UNITED STATES PATENT OFFICE.

EDWARD C. KAHN, OF MILWAUKEE, WISCONSIN.

HOOD FOR FLASH-IGNITERS.

1,175,527.

Specification of Letters Patent. Patented Mar. 14, 1916.

Application filed March 3, 1915. Serial No. 11,919.

To all whom it may concern:

Be it known that I, EDWARD C. KAHN, a citizen of the United States, and resident of Milwaukee, in the county of Milwaukee and State of Wisconsin, have invented certain new and useful Improvements in Hoods for Flash-Igniters; and I do hereby declare that the following is a full, clear, and exact description thereof.

10 My invention refers to the general type of hooded flash torch utilized for igniting grouped gas stove burners, and has for its object to provide a simple, economical and effective hood for such flash torches.

15 Heretofore, so far as I am aware, the general practice has been to utilize either an open top hood for incasing the gas supply head or a closed dome hood. Practice has demonstrated that where an open top hood 20 has been employed, cross-currents of air frequently snuff out the constantly burning pilot-light and hence the closed dome type of hood is the preferable construction. Objections have been found, however, to a dome 25 wholly closed in the top portion for the reason that the constantly ascending current, composed of the products of combustion, is deflected downwardly by the hood into the path of the incoming fresh air, which feeds 30 the flame, and therefore vitiates it in a manner to interfere seriously with proper combustion and at times to snuff out the pilot light altogether by exclusion of oxygen from the flame. This condition also causes the 35 burning pilot-light to emit obnoxious odors and the partly smothered flame also causes sooty deposits, both upon the burner head and walls of the hood.

My invention is designed to overcome the 40 above referred to objections in a closed hood and it consists essentially in the arrangement of a series of vents disposed above the usual firing ports of such hoods.

Another feature of my invention is to provide a bottom spider for the hood, whereby 45 the same may be conveniently removed for cleansing and the separable construction also renders the device simple in manufacture and convenient in assemblage.

50 With the above objects in view the invention consists in certain peculiarities of construction and arrangement of parts as set forth hereinafter with reference to the accompanying drawings and subsequently 55 claimed.

In the drawings Figure 1 represents a

sectional elevation of a gas-supply head incased within a hood embodying the features of my invention, and Figs. 2 and 3, perspective views of the dismantled hood members.

Referring by characters to the drawings, 1 represents a gas-supply head provided with a series of radially disposed apertures 1' for the discharge of a corresponding series of 65 jet flames to associated gas stove burners, not shown. The head is supplied with gas under valve control, whereby restricted quantities of the gas are caused to flow from the apertures to form a constant burning 70 pilot-light and when the flow of gas is increased the auxiliary volume will cause a series of jet flames to be emitted from the head; as indicated in Fig. 1 of the drawings. All of the above described mechanism, how- 75 ever, forms no part of my present invention.

The hood elements, which are designed to incase any type of head, comprise a spider 2 in the form of a circular disk having a central aperture therein provided with a 80 downturned flange 2' for engagement with the head. The rim of the spider is provided with an upturned flange 2'', from the edges of which a series of inwardly offset and upwardly projecting tongues 4 extend. The 85 body of the disk is provided with a series of air inlet apertures 5, whereby oxygen is supplied to the head for proper combustion. Removably seated upon the spider is an inverted cup-like hood 6, the side walls 6' 90 of which are provided with a series of depressions 6'' extending for a predetermined distance from its mouth adapted to have sliding engagement with the tongues of the spider. The side walls of the hood are also 95 provided with a series of firing ports 7, which are so positioned with relation to the tongue-receiving depressions as to register with the firing apertures of the head.

The side walls of the hood are also provided with a series of vent apertures 8 positioned just below the dome wall 6''' of the hood, as shown, which vent apertures are so proportioned with relation to the air inlet apertures 5 of the spider as to produce perfect combustion with relation to the constantly burning pilot-light.

From the foregoing description it is apparent that, owing to the hood vents above the firing apertures, there is no liability for 110 the accumulation of a strata of vitiated air or products of combustion above the burner

head to flatten or snuff out the pilot-light. This result is due to the fact that the proper amount of oxygen is admitted from below for combustion and the spent products are carried off through the vent openings 8. Furthermore, it will be seen, owing to the fact that the air intake apertures 5 and vent apertures 8 are uniformly disposed about the pilot-light, the currents of air entering and discharging from the closed hood will flow uniformly about the head, whereby cross-currents are eliminated, which cross-currents would otherwise snuff out or cause the pilot-light to waver and, as previously mentioned, this construction also eliminates the tendency of the low-burning pilot-light to foul the ports in any way, resulting in obnoxious odors.

I claim:

- 20 1. A substantially closed dome hood for flash igniters comprising an inverted one-piece cup-like member having a series of firing ports therein, and a series of vent apertures above the firing ports.
- 25 2. A substantially closed dome hood for flash igniters comprising an inverted one-piece cup-like member having a series of firing ports therein, a series of vent apertures formed in the wall of the dome above the firing ports, and a spider for supporting the inverted mouth of the cup-like hood.
- 30 3. A hood for flash igniters comprising an inverted one-piece cup-like member, the side walls of which are provided with firing ports adjacent to its inverted mouth and vent ports adjacent to its top wall.
- 35 4. In a flash torch comprising a burner head having a series of firing apertures therein; the combination of a one-piece closed dome hood for incasing the head, the hood being provided with firing ports in register with said head, and vent apertures above the firing ports.

5. In a flash torch comprising a burner head having a series of firing apertures 45 therein; the combination of a one-piece closed top dome hood for incasing the head, the same being provided with firing ports in register with the head apertures and a series of vent apertures above the firing 50 ports, and a spider for supporting the hood having air inlet apertures therein.

6. A one-piece closed top dome hood for flash igniters comprising an inverted cup-like member provided with a series of firing ports and vent ports above the firing ports, and a spider for detachable connection with the inverted mouth of the cup-like hood.

7. In a flash torch comprising a burner 60 head having a series of firing apertures therein; the combination of a one-piece hood incasing the head and closed at the top, said hood having a series of vent apertures in its side walls adjacent to the top 65 and also having firing ports located below said apertures in registry with the apertures in the head.

8. In a flash torch comprising a burner head having a series of firing apertures 70 therein; the combination of a one-piece hood incasing the head and closed at the top, said hood having a series of vent apertures in its side walls adjacent to the top and also having firing ports located below said apertures in registry with the apertures in the head, and means for supplying air to the hood from the bottom.

In testimony that I claim the foregoing I have hereunto set my hand at Milwaukee in 80 the county of Milwaukee and State of Wisconsin in the presence of two witnesses.

EDWARD C. KAHN.
